SHOE SOLE

M. William Weinberg, Newton Center, Mass., assignor, by mesne assignments, to Continental Oil Company, a corporation of Delaware

Filed Nov. 16, 1964, Ser. No. 82,641

Term of patent 14 years

(Cl. D7—5)

FIG. 1 is a perspective view of a shoe sole showing my new design; and

FIG. 2 is an enlarged fragmentary perspective view of a portion of the shoe sole shown in FIG. 1.

This is a continuation-in-part of pending application Serial No. D. 77,365, filed November 12, 1963, and now abandoned.

I claim:

The ornamental design for a shoe sole, substantially as shown and described.
